UNITED STATES PATENT OFFICE.

ALEXANDER McDougall, OF DULUTH, MINNESOTA.

CONVEYING APPARATUS.

SPECIFICATION forming part of Letters Patent No. 794,877, dated July 18, 1905.

Application filed February 3, 1904. Serial No. 191,833.

To all whom it may concern:

Be it known that I, ALEXANDER McDougall, a citizen of the United States, residing at Duluth, in the county of St. Louis and State 5 of Minnesota, have invented new and useful Improvements in Conveying Apparatus, of which the following is a specification.

My invention, broadly considered, relates to improvements in conveying apparatus and 10 in which ore having sand mixed therewith is conveyed to a mechanism through which the ore is conveyed and separated from the sand and during which separation is subjected to a flow of water. The sand after being separated 15 from the ore together with the water used in the separating process are deposited in a suitable reservoir from which the sand and water are removed to a distant point and the sand deposited upon a dump, the water drained 20 from the dump into a suitable reservoir or equivalent receiver, and the water returned from this receiver to the reservoir to be used over again, whereby the water is repeatedly used for conveying purposes, all of which 25 will be fully described hereinafter.

In the accompanying drawings, Figure 1 is a vertical sectional view of an apparatus embodying my invention. Fig. 2 is a transverse sectional view on the line 2 2 of Fig. 1, 30 showing more clearly the ore-chutes and a car or cars adapted to receive the cleansed and separated ore. Fig. 3 is a perspective view showing the general arrangement of the different parts of my apparatus.

My apparatus is here shown in conjunction 35 with any suitable form of conveyer, by means of which the ore is conveyed from the mine into my improved conveying and separating apparatus.

Referring now particularly to the drawings, 40 1 indicates a mine shaft or opening, from which passes any suitable form of conveyer. As here shown the conveyer 2 is of the skipper form, and, as illustrated in Fig. 2, one of the 45 skippers 3 is dumping its load into the hopper 4 at the upper end of the separating mechanism of my apparatus. The hopper 4 is provided with an inclined bottom 5, and this inclined bottom 5 is provided with a plurality of riffles 6, preferably in the form of

railroad-rails, though other forms may be provided. Located at a point in a plane below the hopper 4 is a suitable screen 7, and a spout 8 establishes communication between the lower portion of the hopper 4 and the 55 inlet end of the screen 7. The screen 7 is placed at a suitable angle, as shown, and a stream of water is supplied to the hopper 4 through the medium of a suitable pump 9 and a pipe 10, having its outlet end leading 60 into the hopper 4. From the foregoing it will be observed that the ore as it is received from the mine with sand mixed therewith is subjected to a stream of water as it is falling into the hopper 4, and this stream of water 65 vigorously agitates the ore, which materially assists in the separation of the sand therefrom, and when the ore and the sand strike the bottom of the hopper the flow thereof and also the flow of the water is retarded by the riffles 70 6, which also materially assists in the separating operation. When desired, there may be several of these separating-screens, and as here shown there are three, and they are located in vertical alinement and constitute the 75 separating mechanism of my conveying apparatus. The several screens 7 have relatively graded sized openings, the large openings being in the upper screen, relatively smaller openings in the intermediate screen, 80 and still smaller openings in the lower screen, whereby the larger pieces of ore roll out of the upper screen 7 and the finer pieces, together with the sand and water, fall therethrough into a suitable sluice 11 and pass 85 through the spout 8 therebelow into the intermediate screen, and the particles of ore too large to pass through the openings or mesh of the intermediate screen 7, together with the sand and the water, fall therethrough into the 90 similar sluice 11 therebelow and into the lower screen 7. The final or lower screen 7 has its openings of such a size as to separate nearly all of the ore from the sand; but the very fine particles will fall therethrough into a similar 95 sluice 11, located therebelow, and this mixture of fine ore, sand, and water is conveyed from the lower sluice 11 to a spout 12 into an overflow-hopper 14. The ore 15, which is rolling from the several screens 7, falls onto 100

suitable chutes 16 and is conveyed by these chutes to cars 17 or to any suitable point. If the ore is to be collected in its graded condition, the several chutes will convey it into separate cars, as illustrated, or to separate receivers.

Located below the overflow-hopper is a suitable reservoir 18, into which the overflowing sand and water fall. The heavier particles of ore 19 will settle at the bottom of this overflow-hopper 14 and can be removed therefrom periodically through the medium of a suitable valve-outlet 20.

As here shown the pump 9 obtains its water-supply from the reservoir 18 through a pipe 21, whereby the water for separating the sand from the ore is repeatedly used, and the reservoir 18 may be replenished with water from the mine or other source, should it become necessary to do so.

As illustrated, the sand will settle at the bottom of the reservoir 18 and is removed therefrom through the medium of a suitable pump 22 and conveyed through the pipe 23 to a distant sand-dump 24. Located adjacent the sand-dump 24 is a suitable receiver 25, which may consist of low land or a cavity, as here illustrated, and the water drains from the sand-dump 24 into the receiver 25. By means of a pump 26 the water is conveyed from the receiver 25 through the pipes 27 and 28 back to the reservoir 18 to be again used through the medium of the pump 9 for separating the sand from the ore.

From the foregoing description it will be observed that my conveying apparatus provides means for removing sand and water to a distant point, collecting the water and returning it to the point at which the sand is deposited to be again used for the purpose of conveying the sand there deposited to a distant dump, and it includes means for conveying sand and water to a point in the form of a reservoir to be removed therefrom to a dump, the water drained from the dump and collected and returned to the sand and water collecting reservoir.

As here shown the screens 7 are of the stationary form; but it will be readily understood that they may be of any other desired form. The several forms being so well known in the art, it is deemed sufficient for the purpose of illustrating my invention to show the stationary form of screen.

I prefer to use a centrifugal form of pump, (as here illustrated,) though it will be readily understood that other suitable forms of pumps may be utilized without departing from the scope and spirit of my invention.

My apparatus is adapted for use in washing ore, phosphate-rock, or other substances, depositing the refuse matter and water into a reservoir and removing the refuse, draining the water from the dump and collecting it,

and returning it again to the reservoir, thereby using it repeatedly for conveying purposes.

In carrying out my invention any suitable form of conveyer may be used to convey the ore to the separator, and the separator may consist of one or more screens, according to the requirements of the particular kind of ore being handled.

Having thus described my invention, what I claim, and desire to secure by Letters Patent, is—

1. In a conveying apparatus, the combination of a reservoir, separate liquid and substance supply to said reservoir, a conveyer for conveying the combined liquid and substance to a point distant from said supply, a receiver adapted to receive the water from the deposited substance, and a conveyer conveying the water from the said receiver back to the reservoir, whereby the same water is repeatedly used for the conveying purposes.

2. In a conveying apparatus, the combination of a settling-reservoir, separate water and sand supplies to said reservoir, whereby the sand will settle to the bottom of the reservoir, a conveyer extending to the bottom of the reservoir to engage the sand, and adapted to convey the water and sand to a distant dumping-point, a receiver located adjacent the dumping-point and adapted to collect the water therefrom, and a water-conveyer for conveying the water from the said receiver back to the reservoir, whereby the same water is repeatedly used for conveying purposes.

3. A conveying apparatus, including a reservoir, a material-supply independent of the reservoir, a water-conveyer connected to the reservoir and subjecting the mineral to a separate supply of water as it is fed to the reservoir, to separate the sand therefrom, a conveyer adapted to convey the sand and water of the reservoir to a distant dump, a receiver adapted to collect the water from the said dump, and a conveyer for conveying the water from the receiver back to the reservoir.

4. A conveying apparatus including an ore-separator, means for conveying the ore to the inlet end of the separator, a water-supply to the inlet end of the separator, a reservoir adapted to receive the water and the separated material from the said separator, a conveyer connected with said reservoir and adapted to convey the separated material and the water to a distant dump, a receiver adapted to collect the water from said dump, and a conveyer for conveying the water from the said receiver back to the reservoir.

5. A conveyer including an ore-separator, a conveyer adapted to convey the ore to the inlet end of the separator, a water-supply to the inlet end of the separator, an overflow-hopper adapted to receive the water and separated material from the separator, a reservoir adapted to receive the separated material and the

water from the outlet of the separator, a conveyer adapted to convey the water and separated material to a distant dumping-point, a receiver adapted to collect the water from the 5 dumping-point, and a conveyer conveying the water from the receiver to the reservoir.

In testimony whereof I have hereunto set

my hand in the presence of two subscribing witnesses.

ALEXANDER McDougall.
